UNITED STATES PATENT OFFICE.

EDWARD MILTON WILDEY, OF LONDON, ENGLAND.

MACHINE FOR USE IN RELIEVING, CUTTING, SHAPING, PROFILING, AND THE LIKE PROCESSES.

Application filed November 22, 1920. Serial No. 425,762.

To all whom it may concern:

Be it known that I, EDWARD MILTON WILDEY, a subject of the King of Great Britain, residing at London, England, have 5 invented certain new and useful Improvements in and Relating to Machines for Use in Relieving, Cutting, Shaping, Profiling, and the like Processes, of which the following is a specification.

10 This invention relates to improvements in and relating to machines for use in cutting, shaping, profiling and the like processes, having a pivotally mounted tool-holder and means such as a cam element for imparting 15 an oscillating movement thereto.

The invention is particularly adapted for use in machines for relief cutting and shaping or forming work, such as gear cutters, 20 reamers, hobs, but is also adapted to operate with other machines of the general character above referred to.

The invention is particularly adapted for use in machines for relief cutting and shaping or forming work, such as gear cutters, 25 reamers, hobs, but is also adapted to operate with other machines of the general character above referred to.

An object of the present invention is to provide an improved apparatus which may 30 be used as an attachment to a lathe or as an independent machine, whereby machine processes of the kind hereinabove referred to can be efficiently and economically carried out.

35 Under the present invention the magnitude of the angular oscillations of the tool-holder is varied independently of the shape of the cam element for imparting an oscillating movement to the tool-holder. Thus 40 in apparatus of the kind set forth having a pivotally mounted tool-holder and means such as a cam element for imparting an oscillating movement thereto, there is provided co-operating connecting mechanism 45 between the tool-holder and the cam element with adjustment for varying the magnitude of the angular oscillations of the tool-holder, so that, for example, the amount of relief can be varied at will quite independently of the cam element.

Further with connecting mechanism according to the present invention for imparting movement to the tool-holder, and connected thereto so that a pull over of the holder is imparted in lieu of the customary 55 push over, rigidity of the tool-holder is ensured and chattering eliminated.

Advantages under the present invention comprise a remarkable speed of production as a manufacturing machine tool, general 60 utility in the workshop; its adaptability for a number of operations that would otherwise require special machines; and in the form of the invention hereinafter described and illustrated in the drawings a comparatively inexpensive attachment which enables 65 relieving work to be carried out on an ordinary lathe.

The accompanying drawings illustrate an embodiment of the present invention in the 70 form of a relieving attachment for a lathe.

In the drawings, Fig. 1 is an end view in the direction of the arrow A, Fig. 3, Fig. 2 an end view in the direction of the arrow B, Fig. 3, Fig. 3 a front view, Fig. 4 a back 75 view, Fig. 5 a plan view, Fig. 6 a sectional plan view on the line C—C, Fig. 2, and Fig. 7 is a plan of a rocking arm hereinafter referred to.

A relieving attachment for a lathe illustrated in the accompanying drawings comprises a base plate 1 fastened to the first slide on the lathe saddle. On the plate 1 is slidably mounted a bracket 2 adjustably positioned by a fitting strip 3. On a shaft 4, mounted in the lower front portion of the bracket 2 and extending through each side thereof, is pivotally mounted a rocking tool-holder 5. The cutting tool 6 is held in the tool holder 5 by means of a set 80 screw 7. Suitable provision is made for packing up the tool to keep the cutting edge in an effective position. At each end of the shaft 4 is an adjustable cap 8, 8, locked in position by set screws 9, 9. The caps 8, 8, fit closely into recesses 10, 10, of the base plate and support the outer ends of the shaft 4. The tool holder is given a rocking movement on the shaft 4 by means of a link 11 one end of which is secured to 100

the tool holder by a bolt 12, and the other end is mounted on a sliding bolt 13 which is adjustably carried in a T shaped slot of an arm 14. This arm 14 is integral with 5 or fixed to a shaft 15 mounted in the upper part of the bracket 2 and projects there-through.

Mounted in the bracket 2 is a hollow shaft 16 having a universal joint in the form of 10 a ring 17 supported by trunnions 18 in the wall of the shaft 16. The ring 17 supports a second ring 19 by trunnions 20. This ring 19 carries a shaft 21. A sleeve 22 is slidably keyed to the shaft 21. The outer 15 end of the sleeve 22 is suitably mounted for drive by the lathe spindle, and rotates at the same speed and in the same direction as the lathe spindle.

On the shaft 15 is keyed by its boss a lever 20 or arm 23 carrying at its other end on a bolt 24 one end of a link 25, the other end of this link being formed as a hook 26. The hook 26 is supported by a bolt 27 which is adjustable in a T shaped slot 28 in a rocking arm 29. The arm 29 has a boss 30 by which it is mounted on a stud or shaft 31, and a projection 32 for limiting its movement in one direction by contact with a stud or catch 33.

Adjustably secured on the boss 30 of the 30 arm 29 is a second arm 34 which carries a finger or peg 35. The finger or peg 35 is arranged to be adjustable lengthwise. The arms 29 and 34 form a bell crank lever arrangement.

35 On the end of the hollow shaft 16 is fixed a multiple-tooth cam wheel or disc 36, this cam wheel rotating in the same direction as the lathe spindle by virtue of the intervening drive mechanism. The cam 40 wheel 36 operates to impart a rocking movement to the tool holder 5 as will be herein-after described.

The number of teeth in the cam wheel 36 correspond to those in the cutter being relieved or the flutes being cut.

45 The position of the arm 34 carrying the finger or peg 35 can be altered by movement around the boss 30 of the arm 29.

Advancement towards the work axis is 50 made by the tool for every tooth of the cam wheel that successively engages with the finger or peg 35. As each tooth passes the peg the tool, through the intervening mechanism, is returned to its outward position.

55 A spring 38 attached at one end to the bracket 2 and at the other end to the rocking tool holder 5 assists in returning the latter to normal position at the end of its rocking movement.

60 A spring 39 operating on the projection 32 of the arm 29 also functions to assist in the rapid retraction of the tool-holder, this retraction taking place when the finger or peg 35 is pushed out of engagement.

The base plate 1 carries at one end in a lug 65 40 a screw 41, the other end of which screw fits into a screwed portion 42 of the bracket 2, thus providing means for adjusting the bracket along the base plate 1.

The connection between the rocking arm 70 29 and the lever or arm 23 may be broken down by removing the hook 26 from the bolt 27, this allowing free movement of the shaft 15 for the purpose of moving the tool out of contact with the work without altering the 75 position of the tool in the holder.

Referring to the rocking arm 29 it will be seen that it is provided with a part circular slot 28 whereby the pivot of the connecting link 25 may be set at varying distances from 80 the center of the stud or shaft 31. In this way the amount of relief imparted to the work by the motion of the rocking tool holder can be varied from zero up to the maximum provided by the device. It will be obvious that 85 when the link 25 is set at that end of the slot 28 remote from the stud or shaft 31 the maximum relief is obtained, the amount of relief gradually decreasing until the link 25 is set in alignment with the stud or shaft 31 which 90 corresponds to the zero setting.

As shewn in Fig. 2 a scale 29^a is provided on the arm 29, the figures giving the amount of relief in millimetres.

The setting of the link 25 in the slot 28 of 95 the working arm 29 is all that is necessary when the device is to work with cams bearing the same number of teeth, for example 16. But when a particular piece of work necessitates a change of the cam to one bearing a different number of teeth, say for example 8, it is necessary to compensate for the extent of movement whereby a correct amount of relief is obtained, as it is obvious that cams having different numbers of teeth 100 will give varying movements to the bell crank arrangement 29, 34. Thus the setting of the link 25 for a relief of two millimetres with a cam of 16 teeth will not be correct

when a cam of 8 teeth is used. To overcome 110 this objection a compensating scale 42^a is placed on the slotted arm 14. This scale is so arranged that a pointer 43 coincides therewith, each mark on the scale representing a cam with a given number of teeth. The 115 pointer 43 moves in unison with the link bolt 13 in the slot 14. The greater the number of teeth in the cam 36 the further away the bolt 13 is placed from the axis of the shaft 15, so that a greater movement of the tool holder 120 will be effected and therefore compensation is provided for the smaller movement imparted by the increased number of teeth on the cam wheel 36.

From the above it will be understood that 125 the scale 29^a provides for the setting of the parts to give a determined range of relief for a particular cam, and the scale 42 acts

as a guide for setting the parts to allow of a compensating movement for cams having different numbers of teeth. Thus the scale 29^a may be identified as the relief scale, and 5 the scale 42^a as the compensating or teeth scale.

For imparting a to and fro movement to the tool holder 5 along its supporting shaft 4, the arm 23 has provided on a part of its boss 10 gear teeth 44 engaging gear teeth 45 on a boss 47 of an arm 46 which arm is loosely mounted by its boss 47 on a stud or shaft 48 fixed in the bracket 2. The boss 47 is housed between ball thrust bearings 49. The lower 15 portion of the arm 46 carries a roller bearing 50. The rocking tool holder 5 is provided, at the upper part adjacent to the arm 46, with a recess 51 having an adjustable block 52 therein. The block is so fashioned as by 20 a slot or groove 53 that the roller bearing 50 of the arm 46 projects therein and co-acts therewith.

The block 52 being adjustable in the recess 51 the slot or groove 53 can be set at any angle 25 relative to the axis of the shaft 4 on which the tool holder rocks, so that upon movement of the arm 46 the tool holder 5, through the medium of the walls of the slot or groove 53, is moved to and fro along its supporting 30 shaft.

To assist in returning the tool holder 5 to its initial position after each sliding movement along the supporting shaft, there may be provided on each side of the bracket 35 2 a recessed boss 54 housing a spring 55 bearing on a sliding cap or cover 56. Adjacent to the cap or cover and on the rocking tool holder is a screw fitting 57 carrying a ball 58 bearing against the cap or cover 56. The screw fitting 57 is for the purpose of 40 adjusting the pressure of the spring 55.

When imparting sliding movement to the tool holder along the supporting shaft it is necessary to slack back one of the caps 8 on the shaft 4 in the direction it is desired to move the tool holder 5. The other cap remains in its normal position and serves as a stop for the tool holder upon its return to initial position.

50 The mounting of the link 11 is such that the parts will accommodate themselves to the to and fro sliding movement of the tool holder.

The general operation of the attachment 55 illustrated is as follows:—

Motion is transmitted from the lathe spindle through the sleeve 22 and allied parts to the multiple tooth cam wheel 36. The teeth of the cam wheel 36 successively engage the finger or peg 35 and thus impart an oscillatory movement to the bell-crank mechanism 29, 34 on the stud 31. Through the link 25 and the arm 23, the shaft 15 and its slotted arm 14 is also oscillated, and the con-

necting link 11 thus imparts a rocking motion to the tool holder 5.

The tool holder may at the same time be given a to and fro sliding movement along its supporting shaft 4 as previously described.

An arrangement whereby spiral relieving is obtained is as follows:—

On the driving sleeve is provided a key which for ordinary relieving (parallel flutes) engages with a straight keyway 21^a 75 in the shaft 21. For relieving spiral flutes the key is withdrawn from the straight keyway and inserted in a spirally cut keyway, 21^b, the angle of spiral being that required in the work. The tool reciprocations, therefore, gain or lose in phase with the uniformly rotating work, and the required spiral effect is produced. Several different spirals of the same hand may be cut in one shaft.

In another arrangement the work at the same time as it is given angular velocity may have imparted thereto linear velocity.

The gearing for the multiple tooth cam wheel may be of equal ratio or varied up 90 and down according to the nature of the work.

It is possible to dispense with the multiple tooth cam wheel and substitute therefor a wheel having a single cam, speeding up of 95 the drive then being necessary.

When it is not desired to impart a to and fro sliding movement to the tool holder, the means whereby this is effected is rendered inoperative. Or the oscillation of the tool 100 holder may be made inoperative and the to and fro motion only be used. This is effected by placing the sliding bolt 13 to zero position in the slot of the arm 14 whereby the link 11 is not acted on by the shaft 15. Or 105 both motions can be made inoperative and the tool holder used as a slide rest.

Inside relieving for hollow mills, threading dies, and the like can be effected by the use of a cranked tool.

The finger or peg 35 may be adjustable in length.

With a rocking tool holder according to the present invention the cut can be continued close up to the radius face of the tooth, as 115 a rapid retraction or withdrawal of the cutting tool at the end of the cut is effected.

With an apparatus under the present invention face relief and one side relief can be effected in one operation.

For ordinary turning the oscillating movement is dispensed with.

What I claim is:—

1. In apparatus for use in relieving, cutting, shaping, profiling and the like processes 125 the combination of a pivotally mounted tool-holder, a cam element for imparting an oscillating movement thereto, connecting mechanism between the tool-holder and the

cam element and a segmental groove and setting block for varying the magnitude of the angular oscillations of the tool-holder.

2. Apparatus as claimed in claim 1 hereof having means operated by the connected mechanism for imparting a to and fro motion parallel or substantially parallel to the axis of the work.

3. Apparatus for use in relieving, cutting, shaping, profiling and the like processes, comprising a pivotally mounted tool-holder, a cam element, means for driving said cam element, and lever and link mechanism interposed between the tool-holder and the cam element and coupled to the tool-holder substantially as described.

4. Apparatus for use in relieving, cutting, shaping, profiling and the like processes, comprising a rocking tool-holder, a cam element, means for driving said cam element, connecting mechanism interposed between the tool-holder and the cam element, and means dependent on the connecting mechanism for imparting a to and fro motion parallel to the axis of the work, substantially as described.

5. Apparatus for use in relieving, cutting, shaping, profiling and the like processes, comprising in combination a rocking tool holder, a cam element, mechanism interposed between the tool holder and the cam element whereby the movement of the cam element controls the oscillation of the tool holder during the cut, and setting means for varying the amount of relief imparted to the work.

6. Apparatus as claimed in claim 8 hereof wherein the setting means for varying the amount of relief comprises a slotted pivoted element and a link element co-operating therewith.

7. Apparatus for use in relieving, cutting, shaping, profiling and the like processes, comprising in combination a rocking tool holder, a cam element, mechanism interposed between the tool holder and the cam element whereby the movement of the cam element controls the oscillation of the tool holder during the cut, setting means for varying the amount of relief imparted to the work, and compensating means co-operating with the setting means for the purpose described.

8. In apparatus for use in relieving, cutting, shaping, profiling and the like processes, the combination of a rocking tool holder, a cutting tool carried thereby, a controlled feed for the tool holder during the cut, means for driving the said feed, and setting means for varying the amount of relief imparted to the work.

9. Apparatus for use in relieving, cutting, shaping, profiling and the like processes comprising in combination a base plate, a rocking tool holder mounted thereon, a cut-

ting tool mounted thereon, a cutting tool carried by the tool holder, a cam component, means for imparting movement to said cam component, lever and link mechanism interposed between the cam component and the 70 rocking tool holder and operative during the cut to advance or recede the cutting edge of the tool towards or from the axis of the work in an arcuate path, said mechanism being operated and controlled by said cam component and means for returning the rocking tool holder to normal position at the end of the working stroke. 75

10. Apparatus for use in relieving, cutting, shaping, profiling and the like processes comprising in combination a base plate, a rocking tool holder mounted thereon, a cutting tool carried by the tool holder, a cam component, means for imparting movement to said cam component, lever and link mechanism interposed between the cam component and the rocking tool holder and operative during the cut to advance or recede the cutting edge of the tool towards or from the axis of the work in an arcuate path, said 80 mechanism being operated and controlled by said cam component, means for returning the rocking tool holder to normal position at the end of the working stroke, and setting means for varying the amount of relief consisting of a slotted pivoted element and a link element co-operating therewith. 85

11. Apparatus for use in relieving, cutting, shaping, profiling and the like processes comprising in combination a base plate, 100 a rocking tool holder mounted thereon, a cutting tool carried by the tool holder, a cam component, means for imparting movement to said cam component, lever and link mechanism interposed between the cam component and the rocking tool holder and operative during the cut to advance or recede the cutting edge of the tool towards or from the axis of the work in an arcuate path, said mechanism being operated and controlled by said cam component, means for returning the rocking tool holder to normal position at the end of the working stroke, and setting means for varying the amount of relief consisting of a pivoted element having a slot 105 therein; an indicating scale on said pivoted element, a link element one end of which moves in the slot of the pivoted element, and compensating means co-operating with the setting means for the purposes described. 110

12. Apparatus for use in relieving, cutting, shaping, profiling and the like processes comprising in combination a base plate, a rocking tool holder mounted thereon, a cutting tool carried by the tool holder, a 125 cam component, means for imparting movement to said cam component, lever and link mechanism interposed between the cam component and the rocking tool holder and operative during the cut to advance or recede 130

the cutting edge of the tool towards or from the axis of the work in an arcute path, said mechanism being operated and controlled by said cam component, means for returning the rocking tool holder to normal position at the end of the working stroke, and means for imparting a reciprocating movement to

the tool holder at right angles to its rocking movement, said means being operated by the lever and link mechanism.

10

In testimony whereof, I affix my signature.

EDWARD MILTON WILDEY.
